(57) **CLAIM**

We claim the ornamental design for a combination battery and case for electronic equipment, as shown and described.

DESCRIPTION

FIG. 1 is a front perspective view of a combination battery and case for electronic equipment, showing our new design; FIG. 2 is a rear perspective view thereof; FIG. 3 is a front elevational view thereof; FIG. 4 is a rear elevational view thereof; FIG. 5 is a right-side elevational view thereof; FIG. 6 is a left-side elevational view thereof; FIG. 7 is a top plan view thereof; FIG. 8 is a bottom plan view thereof; FIG. 9 is an exploded front perspective view thereof; FIG. 10 is an exploded front elevational view thereof; FIG. 11 is an exploded rear elevational view thereof; FIG. 12 is an exploded right-side elevational view thereof; and, FIG. 13 is an exploded left-side elevational view thereof. The broken line shown in the drawings of the combination battery and case for electronic equipment are included for the purpose of illustrating environmental structure and form no part of the claimed design.
